US0D1030561S

(12) **United States Design Patent** (10) **Patent No.:** **US D1,030,561 S**
(45) **Date of Patent:** **** Jun. 11, 2024**

(54) **MOTORCYCLE**

(71) Applicant: **Indian Motorcycle International, LLC**, Medina, MN (US)

(72) Inventors: **Richard J. Christoph**, Victoria, MN (US); **Brian N. Flick**, Maple Grove, MN (US)

(73) Assignee: **Indian Motorcycle International, LLC**, Medina, MN (US)

(**) Term: **15 Years**

(21) Appl. No.: **29/900,037**

(22) Filed: **Aug. 16, 2023**

Related U.S. Application Data

(62) Division of application No. 29/759,570, filed on Nov. 24, 2020, which is a division of application No. 29/662,947, filed on Sep. 10, 2018, now Pat. No. Des. 911,879.

(57) **CLAIM**

The ornamental design for a motorcycle, as shown and described.

DESCRIPTION

FIG. 1 is a top, front, and left side perspective view of a motorcycle embodying our new design;

FIG. 2 is a top, rear, and right side perspective view thereof;

FIG. 3 is a left side elevation view thereof;

FIG. 4 is a right side elevation view thereof;

FIG. 5 is a top plan view thereof;

FIG. 6 is a front elevation view thereof; and,

FIG. 7 is a rear elevation view thereof.

The broken lines in the drawings illustrate portions of the motorcycle that form no part of the claimed design.

1 Claim, 6 Drawing Sheets
